203,933

LEVER ACTUATED CONTROL KNOB FOR ELECTRONIC EQUIPMENT

Lloyd A. Griffith, 1027 California Drive,
Burlingame, Calif.

Filed Feb. 8, 1965, Ser. No. 83,732

Term of patent 14 years

(Cl. D26—13)

FIG. 1

FIG. 2

FIG. 3

FIG. 4

FIG. 5

FIG. 1 is a perspective view of a lever actuated control knob for electronic equipment, showing my new design.

FIG. 2 is a bottom plan view thereof.

FIG. 3 is a top plan view thereof.

FIG. 4 is a side elevational view as viewed from the right in FIG. 3.

FIG. 5 is a front elevational view thereof.

I claim:

The ornamental design for a lever actuated control knob for electronic equipment, as shown.
